DESIGN FOR A BREAD WRAPPING MACHINE
OR THE LIKE

Thormod Jensen, Laurelton, N. Y., and Herbert Rosengren, Woodcliff Lake, N. J., assignors to American Machine & Foundry Company, a corporation

Original application May 6, 1938, Serial No. 77,042.
Divided and this application December 1, 1938,
Serial No. 81,498. Term of patent 14 years

To all whom it may concern:

Be it known that we, Thormod Jensen, a citizen of the United States of America, residing at Laurelton, in the county of Queens and State of New York, and Herbert Rosengren, a citizen of the United States of America, residing at Woodcliff Lake, in the county of Bergen and State of New Jersey, have invented a new, original, and ornamental Design for a Bread Wrapping Machine or the like, of which the following is a specification, reference being had to the accompanying drawings, forming part thereof.

The present application has been divided from our co-pending application, Serial No. D-77,042, filed May 6, 1938.

The drawings show in Fig. 1 a front perspective view of a bread wrapping machine or the like, illustrating our new design; Fig. 2 is a view of the same in rear perspective; Fig. 3 is a view thereof in end perspective, looking toward the right-hand end of Fig. 1; and Fig. 4 is a view thereof, looking toward the left-hand end of Fig. 1.

We claim:

The ornamental design for a bread wrapping machine or the like, substantially as shown and described.

THORMOD JENSEN.
HERBERT ROSENGREN.
